UNITED STATES PATENT OFFICE.

CHESTER I. HALL, OF CHICAGO, ILLINOIS, ASSIGNOR, BY MESNE ASSIGNMENTS, TO CHICAGO ELECTRIC METER COMPANY, OF CHICAGO, ILLINOIS, A CORPORATION OF ILLINOIS.

BILL-PRINTING MECHANISM.

1,087,902.

Specification of Letters Patent. Patented Feb. 17, 1914.

Application filed June 3, 1911. Serial No. 631,044.

To all whom it may concern:

Be it known that I, CHESTER I. HALL, a citizen of the United States, residing at Chicago, in the county of Cook and State of Illinois, have invented a certain new and useful Improvement in Bill-Printing Mechanisms, of which the following is a full, clear, concise, and exact description, reference being had to the accompanying drawings, forming a part of this specification.

My invention relates to an improved form of bill printing mechanism adapted for use in automatically reading and printing the condition of the counters usually employed in connection with meters for measuring the quantity of gas, electricity, water, etc., which is consumed or passes through the metering mechanism during predetermined intervals.

While my invention is shown in the present case as adapted for use in connection with one particular style of counting mechanism commonly employed in meter construction, it is to be understood that it is equally applicable to other forms and arrangements of counter mechanism and that the bills printed by means of my device may express other quantities than the consumption and price of electrical energy although the sample bills shown and referred to are for that purpose.

By my invention I provide mechanism which may be carried from meter to meter, and which by simple manipulation may be automatically operated to set suitable record making mechanism to correspond with the reading of the meter counter, after which by properly placing a blank bill in the meter reading mechanism it may have imprinted thereon the present reading of the meter, the consumption since the last reading and the price to be charged for such consumption.

The features referred to above, as well as other features characterizing my invention, will appear more clearly from the following drawings illustrating the same, in which—

Figure 1 is a top view of the recording mechanism with the cover and the printing lever removed. Fig. 2 is a side view of the mechanism assembled with the side wall of the casing toward the observer removed to show the working parts employed, such view being taken along the line 2—2 in Fig. 1.

Fig. 3 is an outside view similar to Fig. 2 of the meter reading and printing mechanism assembled. Fig. 4 is a detail view of mechanism employed to intermittently connect portions of the operating mechanism of the recording devices. Fig. 5 is a detail view showing the means employed for re-setting the printing wheels to zero. Fig. 6 is a detailed view showing detent mechanism for holding certain of the printing wheels in the position to which they are moved by the operating mechanism. Fig. 7 is a detailed view of the mechanical construction and arrangement of the circuit controlling mechanism used in connection with each of the orders of printing wheels employed. Fig. 8 is an enlarged detailed view of the first group of printing wheels showing the relation thereto of the carry-over wheels normally connecting them. Fig. 9 is an enlarged, longitudinal, sectional view through the shaft supporting the commutating and switching mechanism, showing a portion of such mechanism employed to control the operation of the recording devices. Fig. 10 is a detailed, sectional view of contact making mechanism employed in connection with the contact block designed to be applied to the counter of the meter to control the circuit connections of the recording mechanism, such view being taken along the line 10—10 in Fig. 11. Fig. 11 shows in diagrammatic arrangement the circuit connections employed for operating and controlling the recording devices. Fig. 12 is a face view of a counter adapted for use with the contact block shown in Fig. 11. Fig. 13 is a bottom view of a portion of the mechanism shown in Figs. 1, 2 and 3. Fig. 14 shows a form of bill that may be used in connection with my printing mechanism, such bill being shown in this figure in the condition that it is before being operated upon by the recording devices. Fig. 15 is a view similar to Fig. 14, showing the bill after having been operated upon by the recording and printing mechanism.

Similar numerals refer to similar parts throughout the several views.

As shown in Figs. 1 and 2, a casing 1 is provided with a plurality of shafts 2, 3 and 4 extending transversely thereof, each of such shafts having loosely mounted upon it a plurality of printing wheels, 5, 6 and 7,

respectively. Immediately below the shafts 2, 3 and 4 a second set of shafts 8, 9 and 10 is disposed, upon which are mounted individually rotatable indicating wheels 11, 12 and 13, respectively. Each printing wheel 5 has secured to it a gear 15, while each of the indicating wheels 11 has secured to it a gear 16 meshing with the gear 15. Carry-over gears 17, supported upon a transverse rod 18 by swinging brackets 19 pivoted to the casing 1 at 20, are provided between adjacent ones of the indicating wheels 11. Each indicating wheel 11 of lower order carries a cam 21 adapted to engage the associated carry-over gear 17 when such wheel passes from nine to zero, as a result of which, since the carry-over wheel is in mesh with the gear 16 carried by the indicating wheel of next higher order, such wheel of higher order is advanced one unit by the carry-over operation. A spring detent 22 is provided in connection with each indicating wheel 11 to retain it in the position to which it is advanced either by the operating mechanism or the carry-over mechanism. The end of the rod 18 is bent into the form of a crank, as indicated in Fig. 1, so that its bent end 18^a may extend through the casing 1 to be engaged by the operator when it is desired to move the carry-over gears 17 upon their pivotal supports 20 from engagement with the gears 16. A spring 23 normally holds brackets 19 in a position to cause engagement between the carry-over gears 17 and the corresponding gears 16. When the carry-over gears 17 are moved from engagement with the gears secured to the associated indicating wheels, they engage a locking bar 19^a carried by the casing 1 to prevent rotation of the carry-over wheels, so that when they are again brought into engagement with the associated gears they will properly mesh therewith.

As seen in Fig. 1, the uppermost printing wheel 5 is the units printing wheel and the gear 14 connected therewith meshes with a driving gear 24 adapted to be operated by the solenoid 25 in a manner to be described. A similar connection is provided between the gears connected with the other printing wheels and the solenoids 25^a, 25^b, and 25^c, the tens and hundreds wheels being operated by engagement between gears 24 and the gears 15, while the thousands printing wheel 5 is connected by a sleeve with its gear 14 meshing with a driving gear 24. Each of the solenoids described controls besides the printing wheels referred to, contact making and controlling mechanism, to be described. Since the mechanism employed between each solenoid and the printing wheel operated thereby is the same as that employed between each other solenoid and the printing wheel driven thereby, but one of such connecting mechanisms will be referred to par-

ticularly in detail. As the mechanism connecting the solenoid 25^c with the printing wheel 5 of highest order is shown in enlarged detail in Fig. 9, this mechanism is selected as illustrative of each of the connecting mechanisms referred to. As shown in Figs. 1, 2 and 9, the shaft 26, which extends transversely of the casing 1, has loosely mounted thereon a sleeve 27 to the upper end of which is rigidly connected the gear 24. The sleeve 27 has also rigidly secured thereto at its lower end a ratchet wheel 28 engaged by the spring pawls 29 and 30 pivotally mounted at 31 and 32 upon a cross-arm 33 carried by the outer end of the plunger 34 of the solenoid 25^c. A spring 35 serves to hold the pawls 29 and 30 normally in the position indicated in Fig. 2. The ratchet wheel 28 and the pawls 29 and 30 are so constructed that when the solenoid 25^c is energized it moves the cross-arm 33 to the position indicated in dotted lines against the adjustable stop screw 36, which rotates the ratchet wheel 28 by means of the pawl 29 a sufficient amount so that the pawl 30 moves into engagement with the next tooth on the ratchet wheel 28. When, subsequently, the energizing circuit of the solenoid 25^c is interrupted, the spring 35 returns the arm 33 to its normal position, thus further rotating the ratchet wheel 28 and parts carried thereby and bringing the pawl 29 into engagement with the next tooth of such ratchet wheel. The combined operation of the pawls 29 and 30 serves to advance the ratchet wheel 28 and the parts carried thereby one-tenth of a rotation so as to advance the associated printing wheel one unit. A guide rod 37 extends from the solenoid 25^c into engagement with the cross-arm 33 to prevent rotation of such cross-arm. The gear 24 has rigidly secured thereto a detent wheel 38 engaged by a spring detent 39, as indicated in Fig. 6, such detent being supported from the plate 40 extending upward from the base 1, a suitable clearance opening 41 being provided in such plate around the sleeve 27. The sleeve 27 also carries a commutator 42 insulated therefrom, which commutator, as indicated in Fig. 7, has at one point in its periphery a block of insulating material 43. The commutator 42 is made of metal and has resting upon its surface a plurality of brushes 44¹, 44², 44³, . . . 44⁹ supported by but insulated from the plate 40. The commutator 42 is in electrical connection with a metallic disk 45 which has ten ratchet teeth in its outer periphery, as indicated in Fig. 7, and is disposed adjacent to a similar ratchet disk 46 of insulating material and of slightly larger external diameter having ten teeth disposed in staggered relation to the teeth of the conducting disk 45. A brush 47 wide enough to rest on the edges of both disks 45 and 46 is supported 130

by and insulated from the plate 40 in a position to engage the teeth of both disks as the disks are rotated.

From the construction just described it will appear that the energization of the solenoid 25° will advance the sleeve 27 and parts carried thereby so as to move the ratchet disks 45 and 46 to cause the brush 47 to engage a tooth of the insulating disk 46 instead of a tooth of the conducting disk 45 and that the return of the plunger 34 to its normal position by means of the spring 35 serves to rotate the disks 45 and 46 to remove the tooth of the insulating disk 46 from engagement with the brush 47 and again bring the brush 47 into engagement with one of the teeth of the conducting disk 45. This operation serves in a manner to be described to control the energizing circuit of the solenoid 25°.

Each of the printing wheels 6 has secured thereto two gears 48 and 49, of which the gears 49 are in substantially the same planes as the gears 15 secured to the printing wheels 5. A rod 50 extends transversely of the casing 1 between the printing wheels 5 and 6 and upon this rod a plurality of gears 51 is mounted, each of which may be moved longitudinally upon the rod 50 to connect a gear 15 with a corresponding gear 49 with which it is in alignment. Pins 52 in the rod 50 prevent the gears 51 from being moved downward, as shown in Fig. 1, a sufficient amount to interfere with the operation of the parts with which they are not designed to come into engagement. Each of the gears 51 is controlled by a crank 53 secured to the end of a rod 54 supported in suitable bearings from the casing 1, such crank 53 being bifurcated at its upper end to receive the gear 51 it controls. The rod 54 has secured to its other end, as indicated in Fig. 2, an operating arm 55, the upper end of which is beveled and insulated, as indicated at 55° in Fig. 1, and so disposed that when the switch rod 56 is moved inward by the switch button 57 against the action of the spring 58 such arm 55 is rotated so as to cause the crank 53 to engage the lower side of the corresponding gear 51, as seen in Fig. 1, and move it into engagement with the corresponding gears 15 and 49. Continued motion of the switch button 57 causes the rod 56 to engage the insulating cam 59 carried by the switch spring 60, as a result of which such switch spring is moved into engagement with the switch spring 61. The switch springs 60 and 61 are supported by and insulated from a block 62 carried by the casing 1, which block constitutes one of the bearings for the rod 54. When the switch button 57 is released the spring 63 serves to return the arm 55, rod 54 and crank 53 to their normal position. This motion of the crank 53 causes a

projecting tooth 53° to engage the teeth of the gear 51 to prevent rotation of such gear when it is out of engagement with the gears 15 and 49, as a result of which when such gear 51 is again moved into engagement it properly meshes with such gears.

Each of the gears 49 meshes with a similar gear 64 secured to one of the indicating wheels 12, as a result of which corresponding ones of the printing wheels 6 and the indicating wheels 12 are similarly advanced by means of the gears 51. Each of the printing wheels 7 has rigidly secured thereto a pinion 65 meshing with a gear 66 carried by one end of the sleeve 67, to the other end of which there is secured a gear 68 meshing with the gear 48. The sleeves 67 are loosely mounted upon a rod 69 extending transversely of the casing 1. Each of the printing wheels 7 has also secured to it a gear 70 meshing with a similar gear 71 secured to the corresponding indicating wheel 13. Each of the indicating wheels 13 except the one of lowest order has secured to it on the opposite side from the gear 71 a similar gear 72 in engagement with a carry-over gear 73. Each of the indicating wheels 13, except the one of highest order, has secured thereto a cam arm 74 for engaging and operating the corresponding carry-over wheel when the indicating wheel to which the arm is secured advances from nine to zero. The carry-over wheels 73 are mounted upon a rod 75, the end 75° of which extends through the casing 1 in a manner similar to the rod 18°, as above described, by which the carry-over wheels 73 may be moved from engagement with the indicating wheels 13, so that such wheels may be re-set to their zero position. The shafts 4 and 10 and the rod 69 are supported within the casing 1 by means of a slideable bracket support 76, so that the gear ratio between the gears 48 and the gears 65 may be changed as desired. The bracket 76 is held in any desired adjustment by means of screws 77.

Each of the indicating wheels 12 carried by the shaft 9 is provided with a spring pawl 78, as indicated in Fig. 5, adapted to enter a groove in the shaft 9, as a result of which when the shaft is rotated in a direction opposite to that of the advance of the indicating wheels it will engage one after the other of the pawls 78 and thus rotate all of the indicating wheels and the parts connected therewith in a backward direction an amount equal to the advance of such wheels when it is desired to set the wheels to zero. A cam 79 is secured to the shaft 9 so that a notch 79° therein will engage a spring pawl 80 carried by the casing 1 when the wheels reach their zero position. Spring detents 81 are provided in connection with the gears carried by the in-

dicating wheels 13 to hold them in any position to which they are moved, so that the carry-over gears will properly register at all times with the gears to be engaged by them when they return after a re-setting operation, and further that the gears engaged by the gears 51 will be held in proper position to mesh with such gears 51 when they are brought into operating position. A milled head 82 is secured to the outer end of the shaft 9, as indicated in Fig. 1, so that the shaft may be rotated to re-set the printing wheels 6 and 7 and the indicating wheels 12 and 13.

The bottom of the casing 1 has sight openings 83 and 84 formed therein through which the readings of the indicating wheels may be observed and thus these sight openings afford a means by which the operator may know the condition of the corresponding printing wheels. Another opening 85 is provided in the bottom of the casing 1 in connection with the indicating wheels 11 to afford a means for acquainting the operator with the condition of these indicating wheels and the associated printing wheels, but this opening 85 is so conformed also that the gears 16 project into such opening so that they may be individually engaged by the operator to set the indicating wheels 11 and the associated printing wheels as is necessary in actuating the mechanisms.

The casing 1 is provided with a cover 86 in which openings 87 are formed immediately over the printing points of the wheels 5, 6 and 7 and platens 88 having facings 89 of suitable resilient material, as rubber or leather, are supported over such openings by means of an operating handle 90. The platens 88 are secured to the handle 90 by rods 91 and a yielding support is afforded by means of springs 92 interposed between the handle 90 and such platens. Nuts 93 on the rods 91 afford a means for adjusting the platens 88 as desired. The operating handle 90 is forked at its left-hand end, as shown in Figs. 1 and 2, and extends downward on the outside of the casing at either side thereof and is secured to the ends of a shaft 94, which shaft has secured thereto within the casing an arm 95 between which and the casing there is disposed a spring 96 which normally serves to hold the operating handle 90 and the platens carried thereby away from the top 86 of the casing to permit the insertion of a bill to be printed between the platens 88 and such top. The arm 95 has extending upwardly to the right therefrom a member 95^a to engage the under side of the top 86 to limit the upward motion of the handle 90.

To provide an inking means for the printing wheels a supply roller 97 supported upon a rod 98 extending transversely of the casing is provided, from which an inked rib-

bon may extend over a guide roller 99 and thus between the printing wheels and the top of the casing 86, from which it passes over a second guide roller 100 to a receiving roller 101 supported upon a rod 102 extending transversely of the casing 1. The receiving roller 101 has secured thereto a ratchet wheel 103 engaged by a spring pawl 104 pivoted to the arm 95 at 105. The pawl 104 is so designed relatively to the ratchet wheel 103 that a single operation of the handle 90 will advance the ribbon 106 an amount sufficient to present a properly inked portion of the ribbon to the printing wheels for each succeeding operation. The receiving roller 101 also carries a second ratchet wheel 107, which is engaged by the spring pawl 108 pivotally supported by the casing 1 to prevent back rotation of the roller 101. A spring 109 is provided to exert a slight resistance upon the roller 97 to maintain the ribbon 106 under proper tension as it is fed around the guide rolls 99 and 100 to the receiving roll 101.

The circuit connections employed in connection with my mechanism are shown diagrammatically in Fig. 11. A contact block 110 of insulating material has mounted thereon four sets of contacts A, B, C, and D, each composed of nine contacts, each of which is constructed as indicated in detailed view in Fig. 10, as follows: A plunger 111 projects somewhat beyond one face of the block 110 from a sleeve of metal in which is contained a spring 112, such sleeve being secured to and forming a part of a plate 113 secured by a screw 114 to the opposite side of the block 110. Means are provided, as indicated, by which the plunger 111 is retained in the sleeve, and the screw 114 serves as a binding post for the wire used to connect the contact to the mechanism to be controlled thereby. The contacts of the different groups A, B, C and D are similarly connected with the brushes of the commutators 42, 42^a, 42^b and 42^c. The contacts of group A are connected by suitable wires, as indicated, so that the individual contacts 1, 2, . . . 9 of contact group A are in electrical connection respectively with the brushes 44¹, 44², . . . 44⁹, and as the other groups of contacts are similarly connected to the brushes bearing upon these commutators particular description of such connection is not required.

The contact block 110 is provided with three conducting plugs 115 adapted to enter conducting bushings 116 secured in the framework of the counting mechanism of the meter 120, as indicated in Fig. 12, and when the plugs 115 are inserted in such bushings the plungers 111 of the different contacts are disposed over the different numerals of the several dials, as a result of which the pointers associated with the dials,

which are in electrical connection with the bushings 116 through the framework of the counter, engage the plungers which are in alinement with them. The plugs 115 are 5 connected together and by a wire 117 with one terminal of the battery 118, the other terminal of which is connected by a wire 119 with one terminal of each of the solenoids 25, 25^a, 25^b and 25^c, the other terminals of which solenoids are connected respectively with the contacts 61, 61^a, 61^b and 61^c. The contacts 60, 60^a, 60^b and 60^c are connected respectively with the brushes 47, 47^a, 47^b, and 47^c. It is to be understood that, 10 while the connecting wires are shown as distributed in Fig. 11 for the sake of clearness, in practice they would be bunched in a single flexible cable extending from the connecting block 110 to the casing 1, within 15 which they are distributed to the several brushes and contacts indicated.

In using my device the operator first selects the bill for the customer whose meter he is about to read and by means of the 20 gears 16, projecting through the casing 1, he sets the indicating wheels 11, after having moved the rod 18^a to the right as indicated in Fig. 3, to the last month's reading indicated on the bill he has selected, as 25 shown in Fig. 14. He then makes sure that the remaining wheels are in their zero position by moving the rod 75^a, as indicated in Fig. 3, to the left and holding it in such position while he rotates the milled head 82 30 around to the left as far as it will go. He then places the contact block 110 in position upon the meter counter 120, which causes electrical contact to be made between the pointers of the several dials and the corresponding contact plungers. The setting of 35 the printing wheels 5 and the indicating wheels 11 to the last month's reading, it will be understood, moves all of the mechanism connected therewith to corresponding 40 positions, as a result of which the insulating segments 43, 43^a, 43^b and 43^c rest under such of the brushes 44¹, 44², etc., as correspond to the position occupied by the respective pointers when the meter was read 45 50 the last time. The operator now presses the switch button 57 corresponding to the units dial which, as above described, first establishes operative connection between the units printing wheel 5 and the units printing 55 wheel 6, and then closes the contacts 60 and 61. If the pointer of the units dial has not advanced from the position occupied at the last reading or occupies the same position as it did at that time, owing to the fact that 60 the insulating segment 43 is under the brush which is in connection with the contact plunger engaging the pointer of the dial, no circuit is closed by the closure of the contacts 65 60 and 61 and thus the solenoid 25 is not energized. In the case shown in Fig. 15 of

the drawings, however, the pointer of the units dial is not in the same position, but is opposite the numeral eight instead of the numeral nine. Thus, when the contact springs 60 and 61 are brought together for this position a circuit is closed as follows: battery 118, wire 119, solenoid 25, contact springs 61, contact spring 60, brush 47, ratchet disk 45, commutator 42, brush 44⁸, contact 8 of contact group A, units pointer of the counter, bushings 116, plugs 115, wire 117, back to battery 118. At this time it is to be remembered the insulating segment 43 rests under the brush 44⁹, as a result of the setting of the printing wheels 5 by the meter reader. 70

The energization of the solenoid 25 first advances the ratchet wheel 28 and parts carried thereby one-half a step or one-twentieth of a rotation, which removes the conducting tooth of the disk 45 from under the brush 47 and places the brush 47 upon a tooth of the insulating disk 46. This interrupts the energizing circuit of the solenoid 25, which thereupon becomes deenergized advances the ratchet wheel 28 the remaining portion of a step of its operation or one-twentieth of a rotation, which again brings the brush 47 into engagement with a tooth of the ratchet wheel 45. This complete operation has moved the insulating segment 43 from under the brush 9 to the position indicated in Fig. 11 and the same operation will be repeated bringing the insulating segment 43 successively under brushes 44¹, 44², 44³, etc., until such insulating segment is brought under the brush 44⁸, since the energizing circuit of the solenoid is maintained through the commutator 42 until interrupted by the insulating segment 43 being brought under the brush which is in electrical connection with the contact plunger engaging the pointer of the units dial. The disk 42^a by the setting operation above referred to was moved to 85 a position such that the insulating segment was under the brush 44⁸ associated with such disk 42^a, and by the advance of the commutator 42 to move the connected printing wheel from nine to zero the carry-over wheel 17 advances the commutator 42^a to bring the insulating segment 43^a under the corresponding brush 44⁴. As this brush is the one in electrical connection with the pointer on the tens dial, it follows that 90 pushing the switch button 57^a does not close an energizing circuit, as a result of which the parts are left in the position to which they are moved by the operation of the solenoid 25. Similarly, there is no 95 change in the position of the parts connected with the commutators 42^b and 42^c, since the pointers of the meter index are in the same position they were at the last 100 reading. It will be readily understood that 105 110 115 120 125 130

if the consumption of energy had been greater than nine units when the switch button 57^a was depressed the commutator 42^a would have been moved around a number of steps corresponding to the number of tens of units of energy consumed, by the circuit closed by the operation of such switch button and similarly for the switch buttons 57^b and 57^c, as a result of which 5 by operating the switch buttons one after the other in the order indicated the printing wheels 5 and the associated indicating wheels 11 are advanced from the position indicating the last month's reading to a 10 position corresponding to the present reading and at the same time the printing wheels 6 and the indicating wheels 12 are advanced from zero to a position to indicate the amount of advance of the index pointers 15 during the interval since the last reading, and at the same time the printing wheels 7 and the indicating wheels 13 are advanced from their zero position to indicate the price of the energy consumed during the interval. 20 25 After the switch buttons 57, 57^a, 57^b and 57^c have been operated as described and the printing and indicating wheels have been properly advanced as a result, so that they indicate the present condition of the 30 meter pointers and the amount of consumption of energy during the last month or interval and the price to be paid for such energy, the bill selected by the operator, which was brought from the office in the condition indicated in Fig. 14, is inserted between the platens 88 and the top 86 of the machine in a position determined by suitable stops 121 and the handle 90 is moved forcibly downward to press the bill against 35 the printing characters under the platens 88, as a result of which the bill appears as indicated in Fig. 15 and may be at once presented to the consumer.

From the above it will appear that by 40 my invention I provide a portable mechanism which may be carried from meter to meter, which mechanism may be operated automatically by electrical means so as to place suitable printing devices in condition 45 to imprint upon a bill or memorandum the present reading of the meter, the amount of consumption since the last reading, and the price to be paid for the amount consumed. I also consider that the make and break 50 mechanism employed in connection with the operating solenoids is novel and that it may be used for other purposes than herein shown without departing from the spirit of my invention. I also wish to have it understood 55 that I consider as novel the means employed for securing any desired rate of operation of the price wheels relatively to the consumption wheels, which rate of operation may be varied as desired.

60 65 While I have shown my invention in the

particular embodiment herein described, I do not, however, limit myself to this construction, but desire to claim any equivalent which may suggest itself to those skilled in the art.

70

What I claim is:

1. In combination, a bill printing machine comprising printing wheels, means for advancing the printing wheels step by step, a connecting member and electrical conductors extending from said means to said connecting member, said connecting member adapted to be temporarily applied to the index of any one of a plurality of meters to cause the operation of the printing wheels 80 in accordance with the indication of the index of any selected meter.

75

2. In combination, a bill printing machine comprising printing wheels, means for advancing the printing wheels step by step, a connecting member, a plurality of sets of contacts carried by said connecting member, and flexible conductors extending from said means to the contacts carried by said connecting member, said connecting member adapted to be temporarily applied to the index of any one of a plurality of meters to establish electric circuit connections through 85 said contacts and so cause the operation of the printing wheels in accordance with the indication of the index of any selected meter.

90

3. In a bill printing mechanism, the combination of two sets of printing wheels normally disconnected from each other, electric mechanism for actuating the first set of 100 wheels, a switch for controlling the operation of the electric mechanism, and a connecting device between the two sets of wheels thrown into operative position by the operation of the switch.

105

4. In a bill printing machine, the combination of two normally disconnected printing wheels, a solenoid for operating one of the wheels, a switch for controlling the operating circuit of the solenoid, and a connecting device brought into position to connect the two wheels by the operation of the switch.

110

5. In a bill printing machine, the combination of a printing wheel, a solenoid for imparting a step by step movement to such wheel, a meter index, electrical connections between the solenoid and the index, and switching means operated by the solenoid for causing its repeated operation until the 115 printing wheel is advanced an amount corresponding to the condition of the index.

120

6. In a bill printing machine, the combination of a printing wheel, a solenoid for advancing the printing wheel by a step by step movement, a meter index, electric connections extending from the solenoid to the index, a switch in the circuit thus formed, and switching devices operated by the solenoid to cause its repeated operation until the 125 130

printing wheel is advanced to a position corresponding to the condition of the meter index.

7. In a bill printing machine, the combination of a printing wheel, a solenoid for advancing the printing wheel by a step by step movement, a meter index, electric connections extending from the solenoid to the index, a switch in the circuit thus formed, 10 switching devices operated by the solenoid to cause its repeated operation until the printing wheel is advanced to a position corresponding to the condition of the meter index, a second printing wheel normally disconnected from the first printing wheel, and mechanism actuated by the switch when operated for connecting the printing wheels.

8. In a bill printing machine, the combination of a printing wheel, a solenoid for advancing the printing wheel by a step by step movement, a meter index, electric connections extending from the solenoid to the index, a switch in the circuit thus formed, switching devices operated by the solenoid 20 to cause its repeated operation until the printing wheel is advanced to a position corresponding to the condition of the meter index, a second printing wheel normally disconnected from the first printing wheel, and 25 mechanism actuated by the switch when operated for connecting the printing wheels before closing the operating circuit of the solenoid.

9. In a bill printing machine, the combination of a printing wheel, a solenoid for imparting a step by step movement to such wheel, a meter index, electrical connections between the solenoid and the index, switching means operated by the solenoid for causing 30 its repeated operation until the printing wheel is advanced an amount corresponding to the condition of the index, and detent mechanism for holding the printing wheel in its operated position.

45 10. In a bill printing machine, the combination of a printing wheel, a solenoid adapted to impart a step by step operation to such wheel, and electric switching devices operated by the solenoid and adapted to determine the number of operating impulses 50 imparted to the printing wheel.

11. In a bill printing machine, the combination of a printing wheel, a solenoid for imparting a step by step motion to such 55 wheel, a commutator having a single insulating segment and driven by the solenoid, brushes bearing upon the commutator, and means for including one of such brushes, the commutator and the solenoid in an electric 60 circuit.

12. In a bill printing machine, the combination of a printing wheel, a solenoid for imparting a step by step motion to such wheel, a commutator having a single insulating 65 segment and driven by the solenoid,

brushes bearing upon the commutator, a second printing wheel normally disconnected from the first printing wheel, a connecting gear, and a switch for including one of such brushes, the commutator and the solenoid in an electric circuit, the operation of such switch serving first to move the connecting gear into operative position to connect the printing wheels and then to close such circuit.

70 13. In a bill printing machine, the combination of a first set of printing wheels, a solenoid connected with each wheel for operating the same by a step by step movement, a second set of printing wheels normally disconnected from the first set of wheels, gears for operatively connecting the corresponding printing wheels of each order, a third set of printing wheels, and intermediate gears of variable ratio between each 80 of the wheels of the third set and the corresponding wheel of the second set.

85 14. In a bill printing machine, the combination of a first set of printing wheels, a solenoid connected with each wheel for operating the same by a step by step movement, a second set of printing wheels normally disconnected from the first set of wheels, a gear for operatively connecting the corresponding gears of each order, a third set of printing wheels, intermediate gears of variable ratio between each of the wheels of the third set and the corresponding wheel of the second set, and a common means for resetting the wheels of the second and third 90 sets to their zero position.

95 15. In a bill printing machine, the combination of a first set of printing wheels, a solenoid connected with each wheel for operating the same by a step by step movement, a second set of printing wheels normally disconnected from the first set of wheels, a gear for operatively connecting the corresponding gears of each order, a third set of printing wheels, intermediate gears of variable ratio between each of the wheels of the third set and the corresponding wheel of the second set, a housing for supporting the wheels of the first, and second sets and a second housing movable relatively to the 100 first housing for supporting the printing wheels of the third set to permit the use of gears of different ratio as desired between the printing wheels of the second and third sets.

105 16. In a bill printing mechanism, the combination of printing wheels, a solenoid for actuating each of such wheels, electrical connections for controlling the operation of each solenoid, and removable carry-over 110 wheels between the printing wheels to permit the individual setting of such wheels.

115 17. In a bill printing mechanism, the combination of printing wheels, a solenoid for actuating each of such wheels, electrical con- 120

nections for controlling the operation of each solenoid, commutating mechanism driven by each solenoid, a contact block adapted to be applied to a meter index to be 5 read, and conductors extending from each commutating mechanism to connectors mounted on such block.

18. In a bill printing machine, the combination of two normally disconnected printing wheels, electric mechanism for operating one of the wheels, a switch for controlling the operating circuit of the electric mechanism, and a connecting device brought into position to connect the two wheels by 15 the operation of the switch.

19. In a bill printing machine, the combination of a printing wheel, an electric mechanism for imparting a step by step motion to such wheel, a commutator having a 20 single insulating segment and driven by said electric mechanism, brushes bearing upon the commutator, and means for including one of said brushes, the commutator and the electric mechanism in an electric circuit.

25 20. In a bill printing mechanism, the com-

bination of printing wheels, an electromagnetic mechanism for actuating each of said wheels, electrical connections for controlling the operation of each electromagnetic mechanism, and removable carry-over wheels between the printing wheels to permit the individual setting of such wheels. 30

21. In a bill printing mechanism, the combination of printing wheels, an electromagnetic mechanism for actuating each of such 35 wheels, electrical connections for controlling the operation of each electromagnetic mechanism, commutating mechanism driven by each electromagnetic mechanism, a contact block adapted to be applied to a meter index 40 to be read, and conductors extending from each commutator mechanism to connectors mounted on such block.

In witness whereof, I hereunto subscribe my name this 31st day of May, A. D., 1911. 45

CHESTER I. HALL.

Witnesses:

ALBERT C. BELL,
CORNELIUS SEATSEMA.
